UNITED STATES PATENT OFFICE

95,014

DESIGN FOR A CIGAR AND CIGARETTE LIGHTER

Bernhard Burger, Jamaica, N. Y.

Application January 28, 1935, Serial No. 55,119

Term of patent 3½ years

To all whom it may concern:

Be it known that Bernhard Burger, a citizen of the United States of America, residing at Jamaica, in the county of Queens and State of New York, has invented a new, original, and ornamental Design for a Cigar and Cigarette Lighter, of which the following is a specification, reference being had therein to the accompanying drawing.

In the drawing:

The single figure is a perspective view, of a cigar and cigarette lighter, showing my new design.

What I claim is:

The ornamental design for a cigar and cigarette lighter, as shown.

BERNHARD BURGER.
